William E. Chester,
by John Elias Jones,

ATTORNEY

UNITED STATES PATENT OFFICE.

WILLIAM E. CHESTER, OF NORWOOD, OHIO.

DENTAL TOOTH-DRILLING TOOL.

1,200,921.

Specification of Letters Patent.

Patented Oct. 10, 1916.

Application filed July 10, 1916. Serial No. 108,509.

To all whom it may concern:

Be it known that I, WILLIAM E. CHESTER, a citizen of the United States of America, and a resident of Norwood, in the county of 5 Hamilton and State of Ohio, have invented certain new and useful Improvements in Dental Tooth-Drilling Tools, of which the following is a specification.

This invention relates to dental tooth-drilling tools and, more particularly, to drills used in preparing the cavities for the upright posts or pins that are set in the tops of tooth-roots for supporting artificial crowns thereon.

15 The details referring to the objects and parts of the structure herein will be fully hereinafter described in connection with the accompanying sheet of drawings, in which latter—

20 Figure 1 is an elevation, partly in section, of the peculiar form of tool used in connection with the post-cavity of a tooth-root, in the upper part of which cavity a boxing is intended to be used, a vertical section of a tooth-root being shown projected axially- 25 below said tool in this view and showing the result of an operation by the tool in forming the post and box cavities therein; Fig. 2, an end view of the active or cutting end of 30 the tool shown in Fig. 1; Fig. 3, an elevation of a similar form of tool to that shown in Fig. 1 but intended for use only in connection with a cavity in a tooth-root that is not supplied with a post-boxing, a tooth-root 35 being also shown in this view projected axially below the tool and showing the result of an action by said tool ready for a post to be used without any boxing in the root; and Fig. 4, an end view of the active or cutting 40 end of the tool shown in Fig. 3.

The tool is composed of an attaching-shank 1 having a flange or collar 2 at its lower end, such flange 2 being circularly grooved or recessed at 3 in its lower face so 45 as to provide for a peripheral, toothed or serrated edge 4 disposed downwardly; a circular-extension 5 having a lower, peripheral, toothed or serrated cutting-edge 6, also disposed downwardly; and a tapered serrated 50 point 7 extending axially from said circular-extension 5. This tool, of the specific form seen in Fig. 1, is adapted to perform service in forming a cavity in the top of a tooth-root, such as that shown in Fig. 1, the tool 55 itself being also shown in that view. The peculiar form of cavity provided in said

tooth-root in Fig. 1 is composed of the usual pulp-canal 9 that has at its upper end a shoulder 10, an expanded-chamber 11, and a still further expanded-chamber 12, the latter being at the top or summit of the root. The largest chamber 12 at the top of the root is provided with a circular-groove 13 in its bottom at its extreme diameter. The two expanded-chambers and the shoulders 60 formed in the top of the pulp-canal of the tooth-root constitute the cavity in which a centrally-orificed boxing or bushing is used for the support of a vertical pin or post, such as is used in tooth roots for supporting 65 crowns, said boxing or bushing being intended to duly reinforce the upper part of the root structure and to form a firm foundation for the crown-supporting post, and neither boxing nor post being shown herein 70 because such details or parts may be of varied structures. In forming the shoulders and enlarged chambers in the upper part of the tooth-root, or rather of its pulp-canal, the lower serrated-edge 6 of the part 5 of the 75 tool is employed to cut the lower shoulder and to ream out the tooth substance for the lesser diameter in the top of the pulp-canal immediately following the advance cutting or drilling of the point 7 into the upper end 80 of said pulp-canal; and then the chamber of largest diameter at the top of the root is reamed out by the serrated-edge 4 and the toothed or serrated bottom 3^a of the circular-groove that is made in the lower face of the 85 flange 2 of the tool, such serrated cutting-face 3^a of that tool being best shown in the end view, Fig. 2. The tool, however, that is adapted to prepare the upper part of the 90 root-cavity for the use of a crown-supporting post, without a boxing or bushing in the upper part of the pulp-canal, is shown in Figs. 3 and 4, and such tool has an attaching-shank 14 that surmounts a flange-portion 15 whose lower peripheral-edge is 95 toothed or serrated at 16 and has an axial-extension 17, the latter being provided with a lower pointed-end 18 that is suitably toothed or serrated for drilling purposes into the upper end of the pulp-canal for the 100 lower end of the upright post that is to be used in the top of the root and extends upwardly beyond the plane of the root for supporting the crown. The toothed or serrated edge 16 of this tool is adapted to ream out 105 or cut the shouldered-portion 19 in the top of the pulp-canal 20 of the tooth-root seen

in Fig. 3, such shouldered-portion being intended for the seating of a flange or collar, or otherwise enlarged part of the upright post used in the root for firmly supporting the crown. It is obvious, though, that the upper part of the root-cavity can be prepared with the form of tool shown in Figs. 3 and 4 for use with a suitable box therein, if desired and necessary.

I claim:

A dental tooth-drilling tool comprising an attaching-shank, a circular, solid flange pro-

vided integrally at one end of said shank and having a peripheral downwardly-toothed reaming or cutting edge and a serrated reaming-surface on its under side within said peripheral downwardly-toothed edge, an axial, integral extension of lesser diameter than that of said solid flanged-portion and having a lower, peripheral toothed-edge, and a tapered, serrated drilling-point concentrically-extended from said last-named axial-extension.

WILLIAM E. CHESTER.
